UNITED STATES PATENT OFFICE.

FRANK E. ETZEL, OF MONTCLAIR, NEW JERSEY.

DAMPER-CONTROLLER.

1,268,443.

Specification of Letters Patent.

Patented June 4, 1918.

Application filed September 27, 1917. Serial No. 193,439.

To all whom it may concern:

Be it known that I, FRANK E. ETZEL, a citizen of the United States, and resident of Montclair, in the county of Essex and State 5 of New Jersey, have invented certain new and useful Improvements in Damper-Controllers, of which the following is a specification.

My invention relates to improvements in 10 means for automatically controlling the operation of dampers, valves and doors of furnaces, boilers and the like, and particularly those utilized in the heating of dwelling houses, whereby the dampers, etc., may be 15 operated substantially at a predetermined time.

The object of my invention is to provide a simple, cheap and readily operable device 20 controllable by the alarm key of an alarm clock, whereby a damper or the like may be operated by such key at a predetermined time, and whereby the clock may be readily applied to and removed from such controlling device in a convenient and expeditious 25 manner.

In carrying out my invention I provide a frame or bracket adapted to support a 30 clock, a rotative member adapted to co-operate with the alarm key of the clock, a lever for connection with the damper, valve or door of a furnace or the like, and a trigger co-operative with said member to retain the lever set until the alarm key has 35 operated said member to permit or cause operation of the trigger for release of the lever for operation of the damper, valve or door.

My invention also comprises novel details of improvement and combinations of 40 parts that will be more fully hereinafter set forth and then pointed out in the claims.

Reference is to be had to the accompanying drawings forming part hereof, wherein,

Figure 1 is a side view illustrating my 45 improvements and a clock co-operative therewith; Fig. 2 is a front view looking from the righthand side of Fig. 1, illustrating the clock in dotted lines and my improvements in position set for operation; Fig. 3 is a detail view illustrating my 50 improvements in operated position; Fig. 4 is a plan view of my improvements; Fig. 5 is a detail perspective of the trigger controlling member, and Fig. 6 is a view illustrating my improvements associated with a furnace.

Similar numerals of reference indicate corresponding parts in the several views.

At 1 is indicated a suitable frame or bracket adapted to be secured to any suitable support and upon which an ordinary alarm clock 2 may be applied. Said clock is shown provided with feet 3 that are adapted to rest in spaced retainers, shown in the form of recesses 4 in the upper surface of frame 1, the rear portion of the clock casing being shown adapted to rest upon a support 5 of frame 1. A coil spring 6 is shown connected at 7 with the clock casing and provided with an eye or loop 8 adapted to be detachably connected with a projection or pin 9 extending from frame or bracket 1. By the means described the clock may be set in position upon frame 1 and spring 6 may be stretched to enable its eye or loop 8 to be attached to projection 9, whereby the clock will be resiliently retained upon the frame or bracket. To remove the clock from the frame or bracket it is merely necessary to release spring 6 from its connection with projection 9, whereby the clock may be lifted off of the frame 1. At 10 is a rotary member pivotally supported upon bracket 1, and adapted to co-operate with the alarm key 2^a of the 55 clock. The member 10 is shown pivotally supported upon a post or pivot 11 carried by an upright 12 suitably secured upon frame or bracket 1, as by one or more screws 13, adjacent to the back of the clock, whereby when the clock is in position upon frame 1, as illustrated in Fig. 1, the alarm key 2^a will register with the member 10 to operate the latter. The member 10 is shown provided with spaced projections 10^a, whereby 60 the key 2^a may be fitted in the space between said projections to co-operate with the latter for rotating member 10. As illustrated, the member 10 is so located with relation to the alarm key 2^a that the latter 65 may oppose the adjacent face of member 10 when the clock is held in position upon frame 1 by spring 6. At 14 is a lever, shown pivotally supported at 15 upon upright 12 on the side of the latter opposite member 10. A trigger or finger 16 is pivotally supported at 17 upon upright 12 to co-operate 70 with member 10 and with lever 14. Said trigger is shown provided with a recess 16^a to receive and coat with a complementary 75 projection 14^a on lever 14 to retain said lever in set position. Said trigger is also shown

provided with a tooth or projection 16^b to coöperate with one or more recesses or notches 10^b in the periphery of member 10, to permit the tooth 16^b to enter the same for 5 release of the trigger from projection 14^a of lever 14 (Fig. 3), and whereby when the tooth 16^b rides upon the periphery of member 10 the recess 16^a of trigger 16 will receive projection 14^a to retain lever 14 in 10 set position (Fig. 2). At 18 is a spring adapted normally to move projection 16^b of trigger 16 toward member 10. I have shown spring 18 connected with a projection 19 extending from trigger 16 and connected with lever 14 at 20, whereby said 15 spring serves the double purpose of drawing the lower end of trigger 16 toward member 10 and drawing lever 14 toward its normal position after it has been released 20 from the trigger.

Lever 14 may be connected with a damper, valve, door or other part to be controlled, in any suitable manner. A chain, cord or the like 21 may be provided with a loop 22 adapted to be connected with the free end portion 14^b of lever 14, when the latter is retained by the trigger 16, substantially as 25 illustrated in Fig. 2. Said end portion 14^b of lever 14 may be suitably shaped, such as 30 illustrated, to retain loop 22 thereon until the lever is released by the trigger, to then permit said loop to be readily disconnected from the lever. Chain 21 may be passed over one or more suitable guiding pulleys 35 23 in an ordinary manner, and may be connected to a damper 24 of a furnace, steam or hot water heater, boiler or the like 25, in any well known manner. I have illustrated the chain 21 as connected with a lever 26, 40 that is pivotally supported at 27 and connected by a chain or the like 28 with the furnace draft door 29, said lever also being connected with damper 24, the parts being so arranged that when chain 21 is released 45 from lever 14, the damper or valve 24 will close and lever 26 will operate to open the draft door 29. The arrangement described for operating the damper, draft door, etc., is merely illustrative of a suitable arrangement 50 for the purpose, and it will be understood that my improvements may be utilized in connection with any suitable means for operating the damper, valve, or door, or one or more of them.

55 In accordance with my improvements, when the alarm key has been wound and the clock has been attached in position upon frame or bracket 1, the alarm key will be set between spaced projections 10^a of member 10, and the key will be retained from 60 rotation by the usual mechanism in the clock for that purpose. When it is desired to set the device to control the furnace damper or the like, the chain 21 will be connected to 65 lever 14, with the latter and the trigger set

in position substantially as illustrated in Fig. 2, and the trigger will retain the lever, in which position the recess 16^a of the trigger will receive the projection 14^a of the lever and the projection 16^b of the trigger will rest upon the periphery of member 10. The tension of chain 21 upon lever 14 is such as to tend to cause said lever to tilt to release the chain, but the trigger 16 then will prevent movement of the lever. When, however, the alarm key operates, (in accordance with the time for which the clock has been set to operate its alarm), said key will rotate as usual, and will engage one or more projections 10^a and thereby cause rotation 70 with the key of member 10, until a recess 10^b of said member registers with the projection 16^b of trigger 16, whereupon spring 17 will pull the trigger, causing its said projection to enter said notch and its recess 85 16^a to rise from projection 14^a, thus releasing lever 14. The tension on chain 21 then will be released and loop 22 will slide from lever 14, permitting the damper to close and the draft door to open. Since the projection 90 16^b of the trigger will now be in a recess 10^b of member 10, the latter thereby will be retained from rotation and such member will in turn check rotation of the alarm key. The clock, of course, will continue 95 to run and its alarm mechanism will operate in the usual way until the time for the next alarm arrives. When the device is next to be set in connection with chain 21, lever 14 will be connected with loop 22 and the trigger 100 will be connected with projection 14^a, whereupon the projection 16^b of the trigger will move out of the recess 10^b of member 10 in which it was resting, and said projection 16^b must next ride against the periphery of member 10 to retain the trigger in 105 locking position with respect to the lever. Usually there will be sufficient tension remaining in the alarm spring of the clock to cause its alarm key to advance slightly when 110 the trigger is removed from the recess 10^b, to cause slight rotation of member 10, to carry its recess 10^b away from projection 16^b of the trigger, whereby the trigger will remain set, resting upon member 10, until the alarm 115 has again released the trigger in the manner before described. In case, however, that the alarm key should not thus rotate slightly the operator may turn the member 10 slightly to present its periphery opposing 120 the projection 16^b. The description just given presupposes that the setting of the devices in connection with chain 21 does not occur at the moment at which the alarm of the clock would operate. After the trigger 125 has once operated it will retain the member 10, and thereby the alarm key, from again operating until the trigger has again been released from recess 10^b of member 10.

In case the key 2^a should bear upon one or 130

more projections 10^a when the clock is set upon the frame, the spring 6 will keep the clock pressed toward member 10, so that when key 2^a rotates it will ride off of said 5 projection or projections and will enter the space between the projections, by reason of the spring 6 pulling the clock toward member 10, the key 2^a then being in position to engage one of the projections 10^a to rotate 10 member 10. Or, the operator may by hand turn member 10 to move projections 10^a away from the key to allow it to enter between the projections.

My invention is not limited to the particular arrangement of parts set forth, since the same may be varied, within the scope of the appended claims, without departing from the spirit of my invention.

Having now described my invention what 20 I claim is:

1. A controller of the class described comprising a lever, a trigger to retain the lever set, a rotary member to control the trigger to cause it to retain or release the lever, 25 said member having spaced projections to receive a clock key therebetween, and a clock having a key coöperative with said projections to operate the member for causing the trigger to release the lever, a support 30 for the clock to retain its alarm key opposing said member, and a spring connecting the clock with the support to retain the clock thereon and resiliently urge said key toward said member.

35 2. A controller of the class described comprising a lever, a trigger to retain the lever, a rotary member having a portion coactive with the trigger to cause it to retain the lever set, and having another portion coöperating with the trigger to permit it to release the lever, said member having spaced projections on one side to receive a clock key, and a clock having a key coöperative with said 40 projections of said member to operate the latter to cause the trigger to release the lever, a support for the clock to retain its alarm key opposing said member, and a spring connecting the clock with the support to retain the clock thereon and 45 silently urge said key toward said member.

50 3. A controller of the class described comprising a lever, a trigger to retain the lever set, a rotary member having a surface coöperative with the trigger to cause the latter to retain the lever and having a recess coöperative with the trigger to cause the latter to release the lever and to stop rotation of said member, and a clock having a key coöperative with the member to 55 operate it to cause the trigger to release the lever and to lock said member and key from further rotation.

60 4. A controller of the class described comprising a lever, a trigger coöperative therewith to retain the lever set, said trigger hav-

ing a projection, a rotary member having a peripheral surface to coöperate with the projection to cause the trigger to retain the lever and having a notch to receive said projection to cause the trigger to release the 70 lever and to stop rotation of said member, and a clock having a key coöperative with the member to rotate it relatively to the trigger to present said recess in position to receive said projection and to stop further 75 rotation of said member and the key.

5. A controller of the class described comprising a frame adapted to support a clock and having a support, a lever and a trigger pivotally carried by the support, said lever 80 and trigger having coöperative means to retain the lever by the trigger, and a rotary member carried by said support and having a portion to coöperate with the trigger to cause it to retain the lever and also 85 having a portion coöperate with the trigger to cause it to release the lever and to stop further rotation of the member, said member having means to coöperate with the clock key for rotation of the member, and a spring connecting the clock with the frame to retain the clock thereon and resiliently urge the key toward the member.

6. A controller of the class described comprising a frame adapted to support a clock 95 and having a support, a lever and a trigger pivotally carried by the support, said lever and trigger having coöperative means to retain the lever by the trigger, and a rotary member carried by said support and 100 having a peripheral portion to coöperate with a portion of the trigger to cause it to retain the lever and having a recess to receive such portion of the trigger to cause it to release the lever and to stop further 105 rotation of the member said member having means to coöperate with a clock key for rotation of the member.

7. A controller of the class described comprising a frame adapted to support a clock 110 and having a support, a lever and a trigger pivotally carried by the support, said lever and trigger having a complementary projection and recess to coöperate for retaining the lever by the trigger, said trigger 115 also having a projection, and a rotary member having a peripheral surface to engage said projection to cause the trigger to retain the lever, said member also having a recess to receive said projection to cause the 120 trigger to release the lever and to stop further rotation of the member, said member being provided with means to coöperate with a clock key, and a spring connecting the clock with the frame to retain the clock 125 thereon and resiliently urge the key toward the member.

8. A controller of the class described comprising a frame adapted to support a clock 130 and having a support, a lever and a trigger

pivotedly carried by the support, said lever and trigger having a complementary projection and recess to coöperate for retaining the lever by the trigger, said trigger also 5 having a projection, and a rotary member having a peripheral surface to engage said projection to cause the trigger to retain the lever, said member also having a recess to receive said projection to cause the trigger 10 to release the lever and to stop further rotation of the member, said lever being provided with spaced projections to receive a clock key therebetween.

9. A controller of the class described comprising a frame adapted to support a clock 15

having feet, said frame having seats for said feet, a spring, means to connect the spring to the clock and frame for resiliently retaining the clock thereon, said frame having a support, a rotary member carried by the support and having means to coact with the key of the clock, a lever, and means interposed between said member and lever for retaining the latter in set position, said member having means to cause said interposed means to retain and release said lever. 20
25

Signed at New York city, in the county of New York and State of New York this 21st day of September, A. D. 1917.
